United States Patent Office

Des. 194,253
Patented Dec. 18, 1962

194,253

DRESSMAKER FORM

Norman Raab, Short Hills, N.J., and Max L. Raab, Philadelphia, Pa., assignors to The Villager, Inc., Philadelphia, Pa., a corporation of Pennsylvania

Filed Sept. 8, 1961, Ser. No. 66,660

Term of patent 14 years

(Cl. D80—8)

FIG. 1 is a front elevational view of a dressmaker form showing our new design;

FIG. 2 is a side elevational view thereof;

FIG. 3 is a top plan view;

FIG. 4 is an enlarged fragmentary perspective view of one of the legs of the base, and

FIG. 5 is an enlarged rear elevational view of the cap.

We claim:

The ornamental design for a dressmaker form, as shown.
